UNITED STATES PATENT OFFICE.

STEPHEN D. HARTOG, OF ST. LOUIS, MISSOURI.

VEHICLE-TIRE.

1,307,123.

Specification of Letters Patent. Patented June 17, 1919.

Application filed February 6, 1917. Serial No. 146,886.

To all whom it may concern:

Be it known that I, STEPHEN D. HARTOG, a citizen of the United States, and a resident of the city of St. Louis, State of Missouri, 5 have invented a certain new and useful Improvement in Vehicle-Tires, of which the following is a specification.

My invention relates generally to vehicle wheel tires and more particularly to a casing 10 for pneumatic or inflatable tires, the principal objects of my invention being to provide a comparatively simple and inexpensive casing which is practically puncture proof; to construct a casing in sections or segments 15 which have interlocking engagement with each other so as to maintain the completed structure in proper assembled relation, which sections can be readily assembled or taken apart; to construct the main body of each 20 section of yielding resilient material, such as rubber, composition or fabric, and to embed therein a plate of metal or analogous material, the same serving as a shield to prevent puncture through the tread portion of the 25 casing section or segment, and to provide the metal plate with a flange, which when the sections are properly assembled occupies a transverse position between an adjacent pair 30 of segments with the outer edge of said flange lying flush with the outer surface of the completed casing, thus in effect serving as a non-skid element and at the same time materially reinforcing the tread portion of the casing and tending to decrease the wear 35 thereupon.

With the foregoing and other objects in view, my invention consists in certain novel features of construction and arrangement of parts hereinafter more fully described, 40 claimed and illustrated in the accompanying drawings in which—

Figure 1 is a side elevational view of a portion of a casing of my improved construction with a part broken away and in section.

Fig. 2 is a plan view of a portion of my improved casing with parts thereof broken away and in section.

50 Fig. 3 is a section taken through the center of one of the casing sections contemplated by my invention.

Fig. 4 is a cross section taken on the line 4—4 of Fig. 3.

Fig. 5 is a plan view of one of the casing 55 segments.

Fig. 6 is a plan view of one of the metal plates which is carried by each segment.

Fig. 7 is a section taken on the line 7—7 60 of Fig. 6.

Fig. 8 is an elevational view of one of the metal plates.

Referring by numerals to the accompanying drawings, 10 designates the body of the casing section or tread segment contemplated by my invention, said body comprising a tread portion 11, side walls 12 and beads 13 all formed integral and composed of yielding and preferably resilient material such as rubber, rubber composition or the 70 same in combination with fabric or suitable fibrous material.

The tread segments thus formed have a cross sectional contour corresponding to the accepted types of casings for pneumatic tires 75 and may be made in any desired and practical length.

Embedded in each segment is a frame plate 14 preferably of metal, so as to form 80 the frame or skeleton for the resilient segment, and so as to also form a puncture protector or puncture proof shield, the same being curved to correspond with the curvature of the tread portion of the segment. One edge of this plate is bent into a plane 85 substantially at right angles to the body of said plate thereby forming an outwardly projecting flange 15 which lies directly against one end of the body of the segment and the edge of said flange lies flush with 90 the tread surface of said segment.

The plate 14 is bent inwardly near its center to form an abrupt shoulder 16 and that portion 17 of said plate beyond this shoulder is concentric with the main body of the plate and necessarily has a smaller radius. Formed integral with the central portion of the member 17 is an outwardly projecting tongue 18, the outer portion of which is offset slightly with respect to the inner portion and formed in said offset outer portion is an aperture 19. A portion at the center of the member 17 is stamped or pressed downwardly to form an outwardly 105 presented hook or tongue 20 the same occupying a horizontal plane slightly below the tongue 18. The plate thus constructed is

embedded in the tread portion of the casing segment with the flange 15 against one end of said segment and with the tongue 18 projecting from the opposite end as shown in 5 Fig. 3.

Formed in the center of the tread portion 11 of the segment and directly beneath the center of the metal plate is a recess 21 which is of sufficient width to accommodate the 10 tongue 18 of the next adjacent segment. (See Figs. 3 and 4.) When the segments thus constructed are in proper assembled relation to form a casing they occupy the positions seen in Figs. 1 and 2 with the 15 flanges 15 of the embedded plates fitting snugly between the ends of an adjacent pair of the segments, with the projecting tongue 18 of each segment inserted through the recess 21 of the next adjacent segment and with 20 the tongue 20 of said next adjacent segment inserted through the aperture 19 of said tongue 18. (See Fig. 1.) This hook and eye engagement between the parts 18 and 20 of the segments holds the same in proper 25 assembled relation and when the inner tube is properly positioned in the casing and inflated a very strong and substantial puncture proof structure is produced.

In assembling or taking the segments 30 apart it is necessary to press an adjacent pair of said segments toward each other with sufficient force to compress the material of which the segments are formed to such a degree as to permit the tongue 20 to be passed 35 through the corresponding aperture 19.

A casing of my improved construction is comparatively simple, can be easily and cheaply manufactured, is puncture proof in its tread portion, is non-skidding in effect by 40 reason of the flanges 15 which are located between the segments, and in the event that any of the segments become worn so as to be unfit for service they can be easily and quickly removed and replaced by new segments. 45

It will be noted that each tread section is provided with a frame or skeleton on which the rubber or resilient body of the section is built, and that these frames are connected or 50 interlocked in such a manner as to flexibly connect the tread sections. It will be understood, of course, that the tongues 18, being constructed of metal and being, therefore, yielding as well as resilient, and each tongue 55 extending into a recess in the adjacent casing sections, the necessary relative movement between the tread section is permitted. These frames, therefore, being connected and interlocked, form a chain around the casing 60 tread, thereby furnishing a strong frame chain as a skeleton or foundation with a resilient body of necessarily weak material as the tread. It will be moreover noted that these frames furnish an efficient protection 65 or shield against punctures.

It will be readily understood that minor changes in the size, form and construction of the various parts of my improved casing may be made without departing from the spirit of my invention the scope of which is 70 set forth in the appended claims.

I claim:

1. A tire casing formed of connected segments, each of which comprises a body of yielding compressible material and a puncture proof shield embedded in the tread thereof, adjacent segments being connected through their respective shields. 75

2. A tire casing formed of segments, each of which comprises a body of yielding compressible material and a puncture proof non-extensible shield embedded therein, each shield having interlocking engagement with the shield in the next adjacent segment. 80

3. A tire casing formed of segments of resilient material, a puncture proof shield embedded in each segment with the shields of an adjacent pair of segments having interlocking engagement with each other. 85

4. A tire casing formed of segments of resilient material, and a puncture protector member embedded in the tread of each section and projecting therefrom, adapted to interlock with a puncture protector member in the next adjacent segment. 90

5. A tire casing formed in segments of flexible material, and a puncture proof shield embedded in each segment, a portion of which shield is bent to form and terminate in a flange, the edge of which flange lies substantially flush with the tread surface of the segment. 95

6. A tire casing formed in segments of flexible material, and a puncture proof shield embedded in each segment, each shield terminating in a portion positioned between the ends of an adjacent pair of segments, with the edges of all the interposed portions of the shields lying substantially flush with the tread surface of the casing. 100

7. A tire casing composed of a series of segmental members, and a frame for and having a part projecting from each member, adapted to interlock with a frame of the next adjacent member. 110

8. A tire casing, comprising, a series of tread segments, and connected frames for and in the treads of said segments.

9. A tire casing, comprising, a series of tread segments, a frame for each segment, and means connecting said frames adapted to connect said segments. 120

10. A tire casing, comprising, a series of tread segments, a frame for each segment, and means connecting said frames adapted to flexibly connect said segments. 125

11. A tire casing, comprising, a series of tread segments, a frame for each segment, and interlocking connections between said frames adapted to connect said segments. 130

12. A tire casing, comprising, a series of tread segments, a frame for and at the tread of each segment, and means on a frame, formed to enter the adjacent segment, adapted to detachably connect said segments.

13. A tire casing, comprising, a series of tread segments, a frame for and at the tread of each segment, and means on a frame, formed to enter the adjacent segment and connecting with its frame, adapted to connect said segments.

14. A tire casing, comprising, a series of resilient tread segments, a frame for each segment, and means connecting said frames adapted to connect said segments.

15. A tire casing, comprising, a series of resilient tread segments, a frame for each

segment, and means connecting said frames, adapted to retain and compress said segments in connected relation.

16. A tire casing, comprising, a series of resilient tread segments, a frame for each segment, adapted to form a puncture protector, and means connecting said frames adapted to connect said segments.

17. A tire casing, comprising, a series of resilient tread segments, a puncture protector frame embedded in each section, and means connecting said frames adapted to connect said segments.

In testimony whereof, I have signed my name to this specification.

STEPHEN D. HARTOG.
